DESIGN.

—o—

A. ROSENSTEIN.
CANE OR UMBRELLA HANDLE.

No. 20,068.

Patented July 29, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,068, dated July 29, 1890.

Application filed June 25, 1890. Serial No. 356,719. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5 which it pertains to make and use it, reference being had to the accompanying drawing, which forms part of this specification.

My invention relates to an improvement in designs for cane, umbrella, or parasol handles; and it consists in the ornamental configuration, which will be more fully described hereinafter, whereby a pleasing and novel effect is produced.

The accompanying photographic illustration 20 represents my invention.

A represents the trunk or portion of a tree, the upper end of which is bent at an angle,

as shown, and which has formed upon its outer end a bird's nest B. Climbing up this tree are two raccoons or other animals C, one 25 of the animals being below the bend of the tree and the other at the point where the bend is made and upon the opposite side of the tree. Below the animal and encircling the tree is any suitable ornamental work D.

Having thus described my invention, I claim—

A design for the handle of a cane, umbrella, or parasol, consisting of the bent trunk or portion of a tree and one or more animals 35 upon the trunk, as herein shown and described.

In testimony whereof I affix my signature in presence of two witnesses.

ALBERT ROSENSTEIN.
